ELECTRICAL APPARATUS

Arthur Dorne, Freeport, N. Y., assignor to United States of America, as represented by the Secretary of War

Application March 29, 1946, Serial No. 657,940

2 Claims. (Cl. 200—1)

1

This invention relates generally to electrical apparatus and more particularly to a switching device for use with high frequency electrical apparatus.

Recent extensive use of high frequency electrical apparatus has created the need for switching devices operable at high frequencies. Conventional switches, operable at low radio frequencies, are unsatisfactory for use at high frequencies because of their geometrical configuration and electrical properties. Even the simple conventional single pole double throw switch, representative of low frequency switching devices, presents an impedance mismatch to lines carrying high frequency currents and has sufficient capacitive coupling between elements to prohibit its use with high frequency circuits. This impedance mismatch and capacitive coupling causes standing waves and undesirable cross talk in high frequency circuits.

The availability of a switching device, operable at high radio frequencies, would find wide usage in electrical apparatus.

It is an object of the present invention to provide a switching device particularly adapted for use in electrical circuits carrying high frequency currents.

It is another object to provide a single pole double throw switch for use with electrical circuits carrying high frequency currents.

It is also an object to provide an electrical switching device which has a low value of capacitance between switching elements and which has a value of characteristic impedance of the order of the characteristic impedance of common coaxial transmission lines.

An electrical switching device, which accomplishes the aforesaid object consists of a rectangular block of metal with a single conventional coaxial transmission line connector attached to one end and with two similar connectors attached to the other end of the metallic block.

Each of the three cable connectors are interconnected by tubular passages cut in the metallic block. These interconnecting passages intersect to form a Y, with the leg of the Y leading to the single connector at one end of the metallic block and with the arms of the Y leading to the pair of connectors at the other end of the metallic block. The periphery of each of these passages forms the outer conductor of one of three intersecting coaxial transmission lines and each passage concentrically encloses a center conductor. Thus, three intersecting coaxial

2

transmission lines are formed. Where the center conductors would normally intersect, a non-metallic plunger is inserted in the metallic block and is fastened to each of the center conductors of the coaxial transmission lines forming the legs of the Y.

These two center conductors, which are fastened to the plunger, are arranged so that when one is in contact with the center conductor of the coaxial transmission line forming the leg of the Y, the other center conductor is grounded to its outer conductor. Longitudinal movement of the plunger reverses the condition of the two center conductors of the coaxial transmission lines forming the legs of the Y.

Other objects, features and advantages of this invention will suggest themselves to those skilled in the art and will become apparent from the following description of the invention taken in connection with the accompanying drawing in which:

Fig. 1 is a plan view of a device embodying the principles of this invention; and,

Fig. 2 is an elevation of Fig. 1 with a portion cut away to show the internal mechanism.

Referring now to Fig. 1, a rectangular metallic block consisting of two similar halves, upper half 10 and lower half 11, is held together by bolts such as 12. A conventional coaxial transmission line connector 13 is attached to one end of the block and two similar coaxial transmission line connectors 14 and 15 respectively, are attached to the other end of the block.

Grooves having a semi-circular cross section are milled in each half 10 and 11 of the metallic block. The grooves cut in half 10 coincide with the grooves cut in half 11, resulting in a passage whose total cross section is in the form of a circle. These passages interconnect the three connectors 13, 14 and 15, and intersect to form a Y with the leg of the Y leading to connector 13 and with the arms of the Y leading to connectors 14 and 15.

The periphery of each of these passages forms the outer conductor of a coaxial transmission line. A center conductor 15 is coaxially contained in the passage leading to connector 13 and similarly, center conductors 16 and 17 are contained in the passages leading to connectors 14 and 15. These center conductors are held in place by spacers 18, 19 and 20. At the intersection of the passages, two spring leaves 21 and 22 are attached to operating plunger 23. An end of leaf 21 is connected to center conductor 16 and an end of leaf 22 is connected to center conductor

17. The other ends of leaves 22 and 23 are silver plated to reduce contact resistance.

Referring now to Fig. 2, it can be seen that longitudinal movement of plunger 28 forces the silver plated end of leaf 21 against the upper half 10 of the metallic block and that the silver plated end of leaf 22 is forced against conductor 15.

Longitudinal movement of plunger 28 in the opposite direction forces the silver plated end of leaf 21 in contact with conductor 15 and forces the silver plated end of leaf 22 in contact with the lower half 11 of the metallic block. The end of conductor 15, which makes contact with leaves 21 and 22, is flattened and is also silver plated to reduce contact resistance. The principle of this device is similar to that of a single pole double throw switch. When plunger 28 is in one position, there is electrical continuity between connector 13 and connector 14, and at the same time, the inner conductor leading from connector 15 is grounded. Consequently, there can be no cross talk between the circuits associated with connector 15 and the circuits associated with the other two connectors. When plunger 28 is in the other position, there is electrical continuity between connector 13 and connector 15, and at the same time the inner conductor leading from connector 14, is grounded. Thus the effect of any capacity existing between parts of the switching device is nullified.

Impedance mismatches due to this switching device are minimized by the proper design of its components. The relative size of the inner and outer conductors of this switching device is proportioned to obtain a characteristic impedance which is comparable in value to the characteristic impedance of commonly used coaxial transmission lines.

A switching device constructed according to the teachings of this specification has been found operable at frequencies as high as 5000 megacycles.

It will be apparent that there may be deviations from the invention as described which still fall fairly within the spirit and scope of the invention.

Accordingly all such deviations are claimed

which fall fairly within the spirit and scope of the invention as identified in the hereinafter appended claims.

What is claimed is:

- 5 1. A switching device for use with high frequency electrical currents including a rectangular metallic block with three intersecting holes drilled in said block to form the periphery of the outer conductors of three coaxial transmission lines, two flexible center conductors each concentrically enclosed by one of said outer conductors of said transmission lines, one rigid center conductor concentrically enclosed by one of said outer conductors of said transmission lines and a non-conducting operating plunger inserted in said metallic block near the intersection of said transmission lines with said flexible center conductors attached to said plunger whereby movement of said plunger forces one of said flexible center conductors into electrical contact with said rigid center conductor and simultaneously the other of said two flexible center conductors is forced into electrical contact with its outer conductor.
- 10 2. A switching device for use with high frequency electrical currents including three intersecting coaxial transmission lines each comprising an outer conductor and a center conductor with two of said center conductors made of flexible material and with the other center conductor made of a rigid material, a control plunger inserted in said coaxial transmission lines at their intersection and attached to said two flexible center conductors whereby movement of said plunger forces one of said two flexible center conductors into electrical and physical contact with its outer conductor and simultaneously the other of said two flexible center conductors is forced into electrical and mechanical contact with said rigid center conductor.
- 15 3. A switching device for use with high frequency electrical currents including three intersecting coaxial transmission lines each comprising an outer conductor and a center conductor with two of said center conductors made of flexible material and with the other center conductor
- 20 4. A switching device for use with high frequency electrical currents including three intersecting coaxial transmission lines each comprising an outer conductor and a center conductor with two of said center conductors made of flexible material and with the other center conductor
- 25 5. A switching device for use with high frequency electrical currents including three intersecting coaxial transmission lines each comprising an outer conductor and a center conductor with two of said center conductors made of flexible material and with the other center conductor
- 30 6. A switching device for use with high frequency electrical currents including three intersecting coaxial transmission lines each comprising an outer conductor and a center conductor with two of said center conductors made of flexible material and with the other center conductor
- 35 7. A switching device for use with high frequency electrical currents including three intersecting coaxial transmission lines each comprising an outer conductor and a center conductor with two of said center conductors made of flexible material and with the other center conductor

ARTHUR DORNE.
